US00D973169S

(12) **United States Design Patent** (10) **Patent No.:** **US D973,169 S**
(45) **Date of Patent:** **** Dec. 20, 2022**

(54) **INFLATABLE SWIMMING POOL**

(71) Applicant: **Shenzhen Paqi Technology Co., Ltd.**,
Shenzhen (CN)

(72) Inventor: **Junhui Huang**, Shenzhen (CN)

(73) Assignee: **Shenzhen Paqi Technology Co., Ltd.**,
Shenzhen (CN)

(**) Term: **15 Years**

(21) Appl. No.: **29/824,820**

(22) Filed: **Jan. 27, 2022**

(51) LOC (13) Cl. **21-03**

(52) U.S. Cl.

USPC **D21/815**

(58) **Field of Classification Search**

USPC D21/811, 818, 819, 832, 835, 814, 815,
D21/816, 803, 797
